UNITED STATES PATENT OFFICE.

ALBERT B. DISS, OF NEWARK, NEW JERSEY, ASSIGNOR TO UNIVERSAL
CASTER & FOUNDRY COMPANY, OF NEWARK, NEW JERSEY, A COR-
PORATION OF NEW JERSEY.

CASTER.

No. 838,307.

Specification of Letters Patent.

Patented Dec. 11, 1906.

Application filed November 7, 1905. Serial No. 286,183.

To all whom it may concern:

Be it known that I, ALBERT B. DISS, a citizen of the United States, residing at Newark, in the county of Essex and State of New Jersey, have invented a new and useful Improvement in Casters, of which the following is a specification.

In casters as usually constructed the part carrying the wheel or roller and to the center of which the lower end of the pintle is secured, and which part is designated as the "jaws," is either formed of cast metal or is cupped up from a blank stamped out of sheet metal. These latter are ordinarily a simple yoke, with which the pintle has only a single point of support; and the object of my invention is the formation of the jaw structure to be cupped up and formed from a blank or blanks of sheet metal of the construction simulating a box-frame through which the pintle passes and in which the same is provided with two points of bearing and support.

In carrying out my invention the blank of sheet metal has a central portion in part circular, with lugs at one side, while from the other side project two jaw members at an obtuse angle to one another, whose free ends are perforated and a projection centrally between these members from the edge of which extends a lug. The central part of the blank is perforated for the pintle, and I provide an auxiliary blank, which when the main blank is cupped up to shape fits within and against the same and is held thereto by the aforesaid lugs, which are bent over upon the surface of the auxiliary blank. This auxiliary blank is centrally perforated for the pintle.

In the drawings, Figure 1 is a vertical section and partial elevation, and Fig. 2 an inverted plan representing the device of my improvement. Fig. 3 is a plan of the preferred form of sheet-metal blank. Fig. 4 is an inverted plan, and Fig. 5 a vertical section and partial elevation, of this blank cupped up to shape. Fig. 6 is a plan of the auxiliary blank, and Fig. 7 a plan of a modified form of sheet-metal blank.

The caster-wheel *a* is of ordinary and well-known character, and the pintle *c* and furniture-leg *d* are also of ordinary and well-known character.

b represents the jaw members, and *b'* the

jaw-frame. The jaw members and jaw-frame are first formed as a blank stamped out of sheet metal, and Fig. 3 shows the preferred form of this blank, in which there is a central circular portion 2, a central perforation 3, lugs 4 at one side of the blank, and from the other side of the blank the jaw members *b* project at an obtuse angle to one another, with the free ends perforated to receive the pivot-pin of the caster-wheel, and between these jaw members *b* there is a projection 5 of the blank with a central lug 6.

The process of cupping up the blank is of course gradual; but when cupped up the jaw members *b* and the rim of the circular central portion 2 form, as shown in Figs. 4 and 5, a continuous wall, in which the jaw members *b* are parallel to one another and the connecting-wall semicircular, the central portion of the blank around the hole for the pintle being flat and substantially at right angles to the jaw members and this back wall, and the parts as cupped up form an inverted-cup configuration.

The projection 5 is drawn at right angles to the flat portion surrounding the hole of the pintle and comes between the jaw members, 80 and the auxiliary blank *e*, stamped up from sheet metal, as shown in Fig. 6, is provided with a central hole for the pintle, with a recess at 7 and a lug at 8, the said auxiliary blank fitting within the cupped-up portion of the main blank, as shown in Figs. 1 and 2, the lug 6 being received in the recess 7 and the lug 8 in the recess between the lugs 4. The lug 6 being bent over upon the surface of the auxiliary blank *e* holds the same against the walls 90 formed at the end of the projection 5. The lugs 4 are also at the opposite side of the auxiliary blank bent over upon the outer face thereof, so as to hold the lug 8 with force against the wall edge of the blank between 95 said lugs, and the shape imparted to this auxiliary blank is such that this outer edge fits snugly within the semicircular wall and adjacent portions of the parallel walls of the jaw members, and the pintle is passed through 100 the holes of the auxiliary blank and main blank, so that its head bears against the outer surface of the auxiliary blank in the position shown in Figs. 1 and 2. This structure forms a very rigid support for the lower end of the 105 pintle and base, from which the parallel jaw

members *b* project to their connection with the caster-wheel, and the manner of attaching the auxiliary blank to the main blank secures the auxiliary blank firmly and permanently in position, and the fact that there are two bearing-points for the pintle insures the pintle maintaining the right relation to the caster-wheel and jaw-frame and prevents a looseness or wobbling of the same, which would cause unnecessary wear at the union of the pintle with the jaw-frame.

In the structure shown in Fig. 7 the main blank is almost identical with the blank shown in Fig. 3, except that between the lugs 4 of the form shown in Fig. 7 there is a V-shaped notch 9. In cupping up the main blank it is somewhat easier to cup up the blank shown in Fig. 7 than the blank shown in Fig. 3, and when the blank shown in Fig. 7 is cupped up the edges of the V-shaped notch 9 are brought closely together, so that in the cupped-up article there is only a line through the metal; but the same is not as strong or as acceptable in its form as the structure cupped up from Fig. 3.

I do not herein limit myself to the number or location of the connecting-lugs and recesses employed, respectively, upon the main and auxiliary blanks.

30 I claim as my invention—

1. In a caster, the combination with the caster-wheel and pintle, of jaw members and a jaw-frame cupped up from a blank stamped out of sheet metal so as to form a hollow structure in which there is a straight rim of circular formation from which the parallel jaw members extend as prolongations, an integral intermediate projection, and an auxiliary blank connected therewith, the pintle passing through perforations in both blanks which provide the same with two bearing-points.

2. In a caster, the combination with the caster-wheel and pintle, of jaw members and a jaw-frame cupped up from a blank stamped out of sheet metal so as to form a hollow structure, in which there is a rim of circular formation from which the parallel jaw mem-

bers extend as prolongations, and an auxiliary blank received within the cupped-up portion of the main blank, and means for connecting the main and auxiliary blanks, the pintle passing through the perforations in both blanks which provide the same with two bearing-points.

3. In a caster, the combination with the caster-wheel and pintle, of jaw members and a jaw-frame cupped up from a blank stamped out of sheet metal so as to form a hollow structure, in which there is a rim of circular formation from which the parallel jaw members extend as prolongations, said blank having a central hole for the pintle, projections 4 at one side, a projection 5 and lug 6 at the opposite sides, and an auxiliary blank received by the configuration of the main blank, and means for connecting the blanks in a fixed relation to one another.

4. In a caster, the combination with the caster-wheel and pintle, of jaw members and a jaw-frame cupped up from a blank stamped out of sheet metal so as to form a hollow structure, in which there is a rim of circular formation from which the parallel jaw members extend as prolongations, said blank having a central hole for the pintle, projections 4 at one side, a projection 5 and lug 6 at the opposite sides, an auxiliary blank having a curved edge and a straight edge, a recess 7 and lug 8 and adapted to fit within the curved portion of the main blank and its straight edge to rest upon the edge of the projection 5, the lug 6 of the main blank being received in the recess 7 of the auxiliary blank and overturned, and the lug 8 of the auxiliary blank received between the said lugs 4 of the main blank and the latter lugs overturned upon the auxiliary blank in connecting the parts together.

Signed by me this 3d day of November, 1905.

ALBERT B. DISS.
